UNITED STATES PATENT OFFICE

FRENCH E. DENNISON, OF BELOIT, WISCONSIN, ASSIGNOR TO NATIONAL REFRIGERATION CORPORATION, OF BELOIT, WISCONSIN, A CORPORATION OF DELAWARE

REFRIGERATING UNIT

Application filed July 21, 1926. Serial No. 123,991.

This invention relates to mechanical refrigerating apparatus, and while its principles may be embodied in apparatus of various sizes, it is particularly adapted for the smaller types known as household refrigerating systems.

One of the primary purposes of my present invention is to provide an apparatus which will be small and compact, so as to occupy a minimum of space, and one which at the same time will be economical to manufacture and operate and which will be efficient and durable in use.

With these ends in view, my invention contemplates the construction of a condenser in tubular form so that a maximum area for the conduction of heat units away from the refrigerant will be exposed, and the mounting of the compressor and the means for driving the same and the means for cooling the motor and the compressor entirely within the condenser, thereby providing a small and compact unit which can be readily mounted upon the top of an ordinary household refrigerator.

Among the desirable features possessed by an apparatus constructed in this manner may be mentioned the following:

The condenser presents a maximum of exposed area in proportion to its cubical content, thereby facilitating the condensation of the refrigerating medium therein and furthermore not only is the exterior of the condenser subject to the cooling effect of the surrounding atmosphere or liquid, but the interior as well is cooled by the flow of air or liquid therethrough induced by the fan or pump, which also cools the motor, the compressor and the condenser.

The motor and compressor are both housed and inclosed within the cylindrical condenser so that they are adequately protected from injury to themselves and their moving parts are covered so as to afford protection against injury to others.

The motor, compressor and fan are all carried on a base which may be slid into and out from the condenser, thereby making the construction easy to assemble and at the same

time easy to disassemble for inspection or repairs.

The structure presents a pleasing and attractive appearance so that it is not objectionable in a kitchen or other conspicuous place and is readily accessible should the necessity for inspection or repairs arise.

These and other objects are accomplished by providing a construction and an arrangement of the various parts in the manner hereinafter described and particularly pointed out in the appended claims.

Referring to the drawings:

Fig. 1 is a longitudinal cross-sectional view showing one embodiment of my improved refrigerating unit, and

Fig. 2 is a perspective view showing my self-contained refrigerating unit mounted on a refrigerating or storage casing.

In illustrating one embodiment of my invention, I have shown the same as comprising a cylindrical hollow or tubular member 10 having outwardly offset ends 11. Mounted on the tubular member 10 in contact with the offset portion 11 is an outer tubular casing 12 forming a tubular chamber 13 between these two tubular members. The opposite ends of the outer tubular casing member 12 are rolled inwardly around the offset portions 11 of the tubular member 10 as shown at 14, so as to embrace these offset portions and secure the outer casing 12 to the inner casing member 10. The chamber 13 formed between these two cylindrical casing members is sealed by having the casing member soldered as shown at 15, or if it is found desirable the adjacent ends of these cylindrical members may be seam-welded. These cylindrical members when thus secured together form a cylindrical condenser unit in which the refrigerant is spread out over a wide area in the tubular chamber, affording a maximum radiation and conduction surface for the refrigerant in the manner illustrated and described in my pending application, Serial No. 120,355, filed July 3, 1926.

Mounted within the condenser is a compressor, generally indicated by the reference character 16. While the compressor shown is of the rotary type, it will, of course, be under-

stood that any other form of compressor such as the reciprocating type may be employed. The compressor 16 is mounted within and positioned at one end of the cylindrical condenser unit and is operatively driven by an electric motor, generally referred to by reference character 17, which in turn is mounted in the other end of the condenser unit and operatively connected with the compressor 16 by the means of the universal or flexible connection 18. Mounted adjacent the universal connection 18 and secured to the shaft of the motor 17 is a rotary fan 19 which is operatively driven by the electric motor for causing the air to circulate through the condenser unit, cooling the electric motor and compressor as well as expediting the condensation of the refrigerant within the chamber condenser 13 of the unit. The electric motor 17 and the compressor 16 are secured to and supported on a base or frame 20. The base or frame 20 consists of a board which is adapted to be mounted within the inner tubular casing 12. The electric motor 17 and compressor 16 are secured to the board 20 in any well known manner so that if it becomes necessary to remove the motor and compressor for the purpose of inspection or repair, they may be readily slid out on the skid or board 20. The refrigerant is supplied to the chamber 13 of the condenser unit by the conduit 21, which communicates with the compressor 16 at one end and is provided with a shut-off valve 22. The valve is connected to the tubular chamber 13 of the condenser unit by a second conduit 23. The refrigerant is discharged from the tubular chamber 13 of the condenser through a conduit 24, which extends through one of the supporting blocks 25, mounted on the refrigerating or storage casing 26 for supporting the complete unit, and communicates through an expansion valve with the expansion coils (not shown) located within the cooling chamber upon which the unit is mounted. The return pipe 26 from the expansion coil extends through the other supporting block 27. The conduit 26 extends through both casing members 10 and 12 and is connected to a second conduit 28 by a union 29. The other end of the conduit 28 communicates with intake side of the compressor 16 as shown at 30.

Both ends of the cylindrical condenser unit are provided with detachable end covers 31 which in turn are provided with peripheral flanges 32 for frictionally engaging the outer ends of the cylindrical casing member 12. These covers 31 are provided with a plurality of perforations 33 which extend around the covers adjacent the periphery and permit the currents of air generated by the fan to pass freely through the unit from end to end. The complete unit is secured to the top of the storage or refrigerating casing 26, or other

suitable part of the refrigerating storage casing 26 by suitable straps 34 which embrace the unit and have their opposite ends secured to the respective blocks 25 and 27 by bolts 35.

In the operation of my improved refrigerating device, the electric motor may be thrown into operation by a thermostatic switch, causing the rotary compressor 16 and fan 19 to be driven thereby. The compressed gas is delivered through the conduits 21 and 23 into the condensing chamber 13 formed between the cylindrical walls 10 and 12. When the refrigerant is discharged into the chamber 13 it is spread over a wide area in a relatively thin sheet to facilitate its condensation, after which it is discharged through the conduit 24 into the expansion coils in the refrigerating casing 26, thence returned through the conduits 26 and 28 back to the compressor.

If for any reason it should be found necessary to remove the electric motor and compressor for inspection or repairs, both covers 31 may be removed from the unit and the union 29 and the pipe 21 disconnected, permitting the board 20 to be withdrawn from one end of the unit, carrying with it the motor 17 and the compressor 16.

From the above description, it will be readily seen that I have not only provided a simple, efficient, and compact refrigerating unit which not only contains the complete parts of the high side of a mechanical refrigerating system, but also utilizes the condenser unit as a casing for inclosing the other parts of the mechanical refrigerating apparatus. It will also be seen that by providing a rotary fan mounted within the unit operatively driven by the motor, the fan in addition to cooling the motor and compressor also expedites the condensation of the refrigerant by causing a rapid circulation of air through the refrigerating unit.

While in the above specification I have described one embodiment which my invention may assume in practice, it will, of course, be understood that the same is capable of modification and that modification may be employed without departing from the spirit and scope of my invention as expressed in the following claims.

What I claim as my invention and desire to secure by Letters Patent is:

1. A refrigerating apparatus comprising a cylindrical condenser open at each end and having a condensing chamber formed in the cylindrical walls thereof, a base slideable in and out from within said walls, and a compressor and means for driving the same both mounted on said base.

2. A refrigerating apparatus comprising a hollow-walled condenser casing, a compressor, a fan and a motor for driving said fan and compressor all removably mounted within said casing, and means for closing the open

ends of the casing to form a compact inclosed unit.

3. A mechanical refrigerating apparatus comprising a base, a refrigerant compressor mounted on said base, a motor mounted on said base and operatively connected to said compressor, a condenser unit comprising a casing in the form of a tube in which said base is mounted and having a chamber in the walls thereof connected with said compressor whereby the refrigerant is supplied to said chamber, and a detachable cap mounted on said casing for completely incasing said motor and said compressor within said condenser casing.

4. A refrigerating unit comprising a base, a compressor mounted on said base, a motor mounted on said base operatively connected to said compressor, and a condenser unit comprising a tubular casing having a chamber therein, in communication with said compressor, said casing supporting and inclosing said base, motor, and compressor.

5. A refrigerating apparatus comprising a cylindrical condenser casing, and a compressor and means for operating the compressor both mounted within and carried by the casing.

6. A refrigerating apparatus comprising a horizontal cylindrical condenser casing, and a compressor and means for operating the compressor both removably mounted within the casing.

In witness of the foregoing I affix my signature.

FRENCH E. DENNISON.
